US00D922829S

(12) **United States Design Patent** (10) Patent No.: **US D922,829 S**
(45) Date of Patent: **** Jun. 22, 2021**

(54) **CONTAINER ENCLOSURE**

(71) Applicant: **BottleKeeper, LLC**, Houston, TX (US)

(72) Inventors: **Matthew T. Campbell**, Cave Creek, AZ (US); **Adam Callinan**, Manhattan Beach, CA (US)

(73) Assignee: **BottleKeeper, LLC**, Houston, TX (US)

(**) Term: **15 Years**

(21) Appl. No.: **29/740,742**

(22) Filed: **Jul. 7, 2020**

Related U.S. Application Data

(63) Continuation of application No. 29/714,002, filed on Nov. 20, 2019, now Pat. No. Des. 889,209, which is a continuation of application No. 29/688,748, filed on Apr. 24, 2019, now Pat. No. Des. 869,909, which is a continuation of application No. 29/670,065, filed on Nov. 13, 2018, now Pat. No. Des. 852,001.

(57) **CLAIM**

The ornamental design for a container enclosure, as shown and described.

DESCRIPTION

FIG. 1 is an isometric view of a front, top, and right side of an ornamental design for a container enclosure; FIG. 2 is a front elevational view of the container enclosure of FIG. 1;

FIG. 3 is a rear elevational view of the container enclosure of FIG. 1;

FIG. 4 is a right side elevational view of the container enclosure of FIG. 1;

FIG. 5 is a left side elevational view of the container enclosure of FIG. 1;

FIG. 6 is a top plan view of the container enclosure of FIG. 1; and,

FIG. 7 is a bottom plan view of the container enclosure of FIG. 1.

1 Claim, 4 Drawing Sheets
